UNITED STATES PATENT OFFICE.

SAMUEL LIPPINCOTT GRISWOLD KNOX, OF MILWAUKEE, AND WALTER FERRIS, OF SOUTH MILWAUKEE, WISCONSIN, ASSIGNORS TO THE BUCYRUS COMPANY, OF SOUTH MILWAUKEE, WISCONSIN, A CORPORATION OF WISCONSIN.

HOISTING APPARATUS.

No. 808,990.

Specification of Letters Patent.

Patented Jan. 2, 1906

Application filed October 22, 1904. Renewed November 29, 1905. Serial No. 289,669.

To all whom it may concern:

Be it known that we, SAMUEL LIPPINCOTT GRISWOLD KNOX, residing at Milwaukee, and WALTER FERRIS, residing at South Milwaukee, county of Milwaukee, State of Wisconsin, citizens of the United States, have invented certain new and useful Improvements in Hoisting Apparatus; and we do hereby declare the following to be a full, clear, and exact description of the invention, such as will enable others skilled in the art to which it appertains to make and use the same.

This invention relates to hoisting apparatus, such as wrecking-cranes and like mechanism, and has for its object to provide means whereby either one of two hoist-blocks may be operated by a single cable and also to provide means whereby the idle hoist-block may be engaged and held clear of the load lifted by the other hoist-block.

To this end the invention comprises a hoisting apparatus having a jib or similar supporting means upon which is suspended two hoist-blocks by means of a single cable anchored at one end to the jib or support and engaging a hoisting-drum at the other end, an intermediate idler-sheave engaged by said cable, a clamp for securing the cable to the jib or support at a point intermediate the hoist-blocks, and a clutch for locking one of the hoist-blocks to the jib, together with a hook or similar engaging member adapted to be brought into coöperation with the idle hoist-block to hold the latter against the jib or support out of the way of the load lifted by the other hoist-block, the clamp, clutch, and hook mechanism being operated by hand-levers and reach - rod mechanism mounted upon the jib or support.

In the particular embodiment of the invention illustrated in the drawings it is shown as applied to a wrecking-crane with the usual type of swinging jib; but it is to be understood that the invention is capable of application to hoisting mechanisms generally where multiple hoist-blocks are employed.

Referring to the drawings, Figure 1 is a fragmentary side elevation of a wrecking-crane embodying the invention. Fig. 2 is a plan view of the forward end of the jib with the hoist-blocks and sheaves omitted to avoid confusion. Fig. 3 is a side elevation thereof,

showing the rope-clamp and the pendular hoist-block clutch and the operating connections therefor. Fig. 4 is an enlarged perspective view, partly broken away, showing the arrangement and coöperation of the pendular clutch and the hoist-block.

Referring to the drawings, A indicates the usual type of railway wrecking-crane car, upon which is mounted the rotary superstructure B, carrying the pivoted jib C and the usual operating mechanism therefor. The jib C is preferably built up of metal sections and has journaled in its forward end idler-sheaves c, d, and e, over which passes an operating-cable x, anchored to the jib at one end by a bolt f and engaging the usual hoisting-drum at the other end.

Suspended in the bights of the cable depending from idlers c and d is the usual double rope-block b, provided with a load-lifting hook, as is common in wrecking-crane practice, while a multiple block a is suspended in the several bights of the cable between the intermediate idler d and the anchor f, the multiple bights of the cable passing over the idler e and the sheaves of the hoist-block a. The block b according to the usual practice is employed for lifting the relatively light loads, while block a is adapted to lift the heaviest loads. It will be seen, therefore, that both of the hoist-blocks are suspended from the single cable x, the course of said cable being as follows: from the winding-drum on the superstructure over the idler c, thence around the sheave in hoist-block b, thence up and over intermediate idler d, about which it takes two or more turns, thence by several bights or turns about the several sheaves in hoist-block a and a corresponding number of sheaves on idler e to the anchor f.

As above described, the purpose of the invention is to operate either of the hoist-blocks a or b by means of the single cable x, and this is accomplished by the following apparatus: A transverse shaft s, journaled on the upper side of the jib and overlying the intermediate idler d, is provided with an eccentric u, upon which is secured a brake-shoe w, adapted to engage the cable as it passes over the idler d and hold said idler and the cable against movement when the brake is thrown on. To operate the brake, a link t, connected to a

crank on the end of the shaft s , serves to rock the latter and cause the eccentric on the opposite end of said shaft to apply or release the brake-shoe. To the lower end of said link is connected an operating device comprising a series of rod-sections v and intermediate bell-cranks y , the other end of the series of rod-sections being coupled to a hand-lever z , pivoted to the side of the jib, so that the brake may be thrown on or off by an operator on the car manipulating the hand-lever z . It will be seen that when the brake is applied the cable is anchored to the idler d , so that no motion is imparted to that portion of the cable which supports the hoist-block a and the latter remains stationary. The part of the cable forward of the idler d , however, may be taken up or paid off by the hoisting-drum and will run freely over the idler c , thereby raising or lowering the hoist-block b .

In order to operate hoist-block a alone, it is necessary to secure hoist-block b to the jib, and to accomplish this suitable clutch mechanism is provided for locking hoist-block b to the under side of the jib and preferably in juxtaposition to the idler c . For this purpose hoist-block b is provided with a strap i' , extending over the top of the sheave of said block, which strap is adapted to be engaged by a clutch carried by a pendular frame. This clutch mechanism consists of the following parts: A U-shaped pendular frame h is mounted upon the shaft g of idler c and is provided with two depending sections h' , which are adapted to pass upon either side of the strap i' to guide the hoist-block b into proper position to be clutched. Journaled in the bottom of the U-shaped yoke h and in brackets extending from opposite sides of said yoke are two short shafts $b' b''$, having lateral wings $c' c''$, respectively, which wings have inwardly-disposed angular fingers $f' f''$, adapted to engage the band of the strap i' . Passing through the wings $c' c''$ is a bolt l' , having a spring m' , which is suitably tensioned by set-nuts o' , which spring tends to force the fingers toward each other, as indicated in Fig. 4. Mounted upon the upper end of the shaft b' is a crank a' , which engages the flanged rim of a collar i , loosely mounted on the shaft g to one side of the idler c . Journaled in the adjacent side plate of the pendular yoke is a short vertical shaft m , upon the lower end of which is mounted a yoke l , in the forward ends of which are slots k , which engage radial pins j on the collar i . On the upper end of the shaft m is an arm n , which is perforated at its forward end to permit a rod o to pass freely therethrough. Said rod o is provided with a suitable collar or set-nut p beyond the arm n and is connected at its opposite end to a crank r , fixed to the shaft s . It will be seen that when the shaft s is rocked by the hand-lever z and the connecting reach-rod mechanism to retract the

rod o , the set-nut p will engage the arm n , thereby rocking shaft m and the fork l connected therewith, which in turn slides the collar i longitudinally of the shaft g and forces crank a' inward, thereby rocking shaft b' and moving finger f' laterally. A stop g' on the shaft b' engages a similar stop g'' on the shaft b'' , so that as shaft b' is rocked by its crank a' shaft b'' will also be rocked in the opposite direction by the engagement of stops $g' g''$, and finger f'' will also be moved laterally, and the two fingers $f' f''$ will be spread apart against the tension of spring m' on the rod l' . If the hoist-block b be now lifted until the strap i' passes between the fingers $f' f''$ and shaft s be rocked in the opposite direction by means of the hand-lever z , the spring m' will force the fingers $f' f''$ toward each other until said fingers slip under the strap i' and clutch the hoist-block b to the jib.

It is to be noted that the pendular yokes h' and v' are pivoted to the shafts of idlers c and e , respectively, so that each of said yokes will always hang vertically in position to engage the corresponding hoist-blocks irrespective of the relation of the jib C—that is to say, whether the said jib be raised or lowered.

In hoisting a load by one of the blocks it is frequently found that the other block will obstruct the load in its upward movement. Hence we have found it desirable to secure the idle hoist-block to the jib so that it will clear the load lifted by the other block. This is effected by means of a hook q' , pivoted to the jib, which is adapted to engage an eye or loop p' on the hoist-block a , so that the latter will be held out of the path of the load lifted by block b . Said hook q' is operated by a reach-rod r' , which is connected at its opposite end to a hand-lever s' , mounted at the foot of the jib adjacent to the hand-lever z , so that as said hand-lever s' is moved backward the hook q' will lock the hoist-block b to the jib, and when said hand-lever is swung in the opposite direction said hook q' will be released from engagement with the hoist-block a .

It is to be particularly noted that the entire control of each of the hoist-blocks is effected from the single cable x and the hand-lever z on the jib, so that the respective hoist-blocks may be operated in all positions of the jib. For example, when it is desired to use hoist-block a to lift a load the hand-lever z is pulled backward—that is, toward the foot of the jib—thereby rocking shaft s to release the cable-brake w and causing rod o to rock the shaft m , which, through the intermediate mechanism above described, spreads the fingers $f' f''$ apart. Hoist-block b is then run up until strap i' passes between the fingers $f' f''$, and upon the operator moving hand-lever z to mid-position the spring m' forces the fingers $f' f''$ under the strap i' , and thereby clutches said sheave b to the

pendular yoke h' , and therefore to the jib. The cable will now run over the sheave in hoist-block b as if the latter were a simple idler, and the hoist-block a may be run up 5 and down at will. In order to employ hoist-block b in lifting, the hand-lever z is swung to its extreme forward position, thereby rocking the shaft s , so that the eccentric u forces the brake w down upon the cable and 10 clamps the same securely to the idler d , thereby anchoring the cable to the jib at said idler d . This may be accomplished, of course, irrespective of the position of the hoist-block a ; but it is preferable in order to distribute 15 the strain on the cable to run said hoist-block a up until it engages the pendular yoke v' .

What we claim as our invention is—

1. In wrecking-cranes and like apparatus, the combination of two hoist-blocks supported from the jib, an intermediate idler-sheave, an operating-cable engaging the hoist-blocks and intermediate sheave, means for locking the cable against motion between the hoist-blocks, and means for locking one of said 25 blocks to the jib, whereby either of said blocks may be operated by the same cable.

2. In wrecking-cranes and like apparatus, the combination of two hoist-blocks supported from the jib, an intermediate idler-sheave 30 on the jib, an operating-cable anchored at one end to the jib and connected to a winding-drum at the other end, said cable engaging the hoist-blocks and the idler, a clamp for locking the cable to the idler, a clutch for 35 locking one of said blocks to the jib, and means for operating said clamp and said clutch, whereby either of said blocks may be operated by the same cable.

3. In wrecking-cranes and like apparatus, the combination of two hoist-blocks supported from the jib, an intermediate idler-sheave on the jib, an operating-cable anchored at one end to the jib and connected to a winding-drum at the other end, said cable engaging 45 the hoist-blocks and the idler, a clamp for locking the cable to the idler, a clutch for

locking one of said blocks to the jib, a hand-lever, and reach-rod connections from the hand-lever to the clamp and clutch, whereby either of said blocks may be operated by the 5c same cable.

4. In wrecking-cranes and like apparatus, the combination of two hoist-blocks supported from the jib, idler-sheaves on the jib adjacent to each of said blocks, an idler-sheave 55 on the jib intermediate the first-mentioned idler-sheaves, an operating-cable anchored at one end to the jib and engaging a winding-drum at the other end, a clamp on the jib for locking the rope to the intermediate idler- 60 sheaves, a pendular clutch on the jib for locking one of the blocks to the jib, a hand-lever, and reach-rod connections from the hand-lever to the clamp and the clutch, whereby either of said blocks may be oper- 65 ated by the same cable.

5. In wrecking-cranes and like apparatus, the combination of two hoist-blocks, an operating-cable therefor, and means for holding the idle hoist-block clear of the load lifted by 70 the other hoist-block.

6. In wrecking-cranes and like apparatus, the combination of two hoist-blocks, an operating-cable therefor, and a hook on the jib adapted to engage the idle hoist-block and 75 hold the same clear of the load lifted by the other hoist-block.

7. In wrecking-cranes and like apparatus, the combination of two hoist-blocks, an operating-cable therefor, a hook on the jib adapt- 80 ed to engage the idle hoist-block and hold the same clear of the load lifted by the other hoist-block, and a hand-lever and reach-rod on the jib for operating said hook.

In testimony whereof we affix our signatures in presence of two witnesses.
